(57) **CLAIM**

The ornamental design for a parking meter, as shown and described.

DESCRIPTION

FIG. 1 is a front elevational view of a parking meter, showing our new design;

FIG. 2 is a right side elevational view thereof, the left side being a mirror image;

FIG. 3 is a back elevational view thereof;

FIG. 4 is a top plan view thereof;

FIG. 5 is a top front right perspective view thereof; and,

FIG. 6 is a bottom plan view thereof.

The broken lines shown in the drawings represent portions of the parking meter that form no part of the claimed design.
